UNITED STATES PATENT OFFICE.

OTTO KONRAD, OF OSHKOSH, WISCONSIN.

FOLDABLE DISAPPEARING BED.

Application filed November 1, 1919. Serial No. 334,969.

To all whom it may concern:

Be it known that I, OTTO KONRAD, a citizen of the United States, and resident of Oshkosh, in the county of Winnebago and

5 State of Wisconsin, have invented new and useful Improvements in Foldable Disappearing Beds, of which the following is a description, reference being had to the accompanying drawings, which are a part

10 of this specification.

The present invention relates to certain new and useful improvements in beds, and refers more particularly to what may be called a foldable disappearing bed.

15 One object of the present invention is to provide a disappearing bed having a foldable spring frame connected with a supporting member, and provided with means operable upon the movement of the spring

20 frame sections to folded position to nest the same upon the supporting member for convenience in positioning the same within the concealing recess.

It is another object of this invention to 25 provide a foldable bed which may be combined with a couch, davenport, or other support to be of sight, and which may be withdrawn after use without disturbing the seat or upper portion of the support in

30 which it is contained.

Another object of my invention is to provide a novel link supporting connection between the supporting member and one of

35 the spring frame sections, whereby said spring section may have a limited vertical movement, but it will at all times be parallel with reference to the supporting member.

A further object of this invention is to 40 provide a slidable supporting member forming what may be termed a drawer for receiving the folded spring frame sections, and carrying the same into a concealing recess, the outer side or face of said sup-

45 porting member forming a part of the outer face of the wall surrounding the concealing recess.

A still further object of the present invention is to provide a disappearing bed including a supporting member and a spring frame having two hingedly connected together sections connected with the supporting member and having means for elevating one of said sections when they are extended,

55 and locking the same in extended position and means for collapsing and disposing the

spring sections within the supporting member when they are moved to folded position.

A more specific object of this invention is to provide a brace bar for the spring 60 frame where its sections are connected together, which is offset to accommodate for the sagging of the spring, and which has means for guiding its offset portion when the spring frame is nested within its supporting member.

With the above and other objects in view which will appear as the description proceeds, my invention resides in the novel construction, combination and arrangement of 70 parts substantially as hereinafter described and more particularly defined by the appended claims, it being understood that such changes in the precise embodiment of the herein disclosed invention may be made as 75 come within the scope of the claims.

In the accompanying drawing, I have illustrated one complete example of the physical embodiment of my invention constructed according to the best mode I have 80 so far devised for the practical application of the principles thereof, and in which:

Fig. 1 is a perspective view of a davenport in connection with which my invention is employed, the spring frame being illustrated as nested within the supporting member, and the supporting member being shown as partly moved to its position outwardly thereof.

Fig. 2 is a perspective view thereof illustrating the bed as in operative position, i. e., with the supporting member exteriorly of the davenport, and the spring frame sections unfolded or in extended position, said view having parts broken away to more 90 clearly illustrate the various details of my invention.

Fig. 3 is an enlarged fragmentary sectional view illustrating the novel guide means for the offset portion of the intermediate spring frame brace rod, said view being taken on the line 3—3 of Fig. 2.

Fig. 4 is a side plan view of my invention illustrating the various parts thereof as in folded position and nested within the 105 drawer-like supporting member which is shown in its outward position, and

Fig. 5 is the side plan view thereof illustrating the parts as in their operative position.

My invention is adapted to be folded or nested within a drawer-like supporting

member 6 which includes a substantially rectangular shaped frame 7 having a sliding connection with guide members 8 which lead into a concealing recess 9, which may be in 5 a wall or the like or else within the bottom of a davenport as illustrated in Figs. 1 and 2. In either case the outer end of the supporting member 6 has secured thereto a board or partition 10 shaped and finished to 10 conform with the exterior appearance of the wall, davenport or the like, in which the bed is adapted to be concealed, and also has secured to its outer end suitable supporting feet 11, so that its outer end when outwardly 15 of its concealing recess will be maintained substantially level with its inner end.

The supporting member 6 has pivoted to each side thereof in space relation as at 12 the lower end of a pair of links 13 having 20 their upper ends pivotally connected with the lower ends of like links 14 having their upper ends pivoted as at 15 to the adjacent side of a bed spring section 16. Each pair of connected together links 13 and 14 25 have secured thereto adjacent their outer ends as at 17 the outer ends of links 18 having their inner ends pivotally connected together as at 19, each set of connected together links 13, 14 and 18 forming what 30 may be termed one section of a lazy tong. The pivots 20 of each pair of connected together links 13 and 14 are connected together and maintained in space relation by an intermediate bar 21 as best shown in Figs. 4 and 35 5 and the pivots 19 of the links 18 have sliding engagement within slots 22 formed in said bar 21.

As will be readily obvious this structure 40 maintains the spring structure 16 at all times parallel with the supporting frame 7, but at the same time permits its ready vertical movement so that the frame 16 may be nested to lie against the frame 7 or may be 45 releasably locked or held in raised position as depicted in Fig. 5 by means now about to be described.

Pivots 23 to the spring frame section 16 is a complementary spring frame section 24 which is readily movable on 50 its pivots 23 to the folded position depicted in Fig. 4 or to the extended position depicted in Fig. 5 in which position its outer end is supported by a foldable support 25 to be later described and its inner end supported 55 by the section 16.

As will be readily understood the adjacent sides of the section 16 and the frame 7 are connected together by the means of the links before described and as their operations 60 are identical but one side will be hereinafter referred to. The innermost pair of link members 13 and 14 have pivotally connected with their pivot 20 the inner lower end of an operating or locking bar 26 which has 65 its outer upper end pivoted as at 27 to the

adjacent side of the section 24 near its pivot 23, but so positioned on a plane beneath that of the pivot 23 that when the section 24 is in its extended position said pivot 27 will lock the link structure before described and 70 retain the same against collapsing. The bar 26 besides locking the links in their extended position as depicted in Fig. 5 provides the means for raising and lowering the section 16 to operative position or to its position nested within the drawer formed by 75 the supporting member.

The operation of this link structure is substantially as follows:

Assuming the spring sections 16 and 24 80 to be in folded position as depicted in Fig. 4 the section 24 is swung on its pivots 23 when it is desired to place the parts in position for use. This movement of the section 24 moves with it the bar 26 which exerts a 85 forward pull on the pivot 20 of the innermost link members 13 and 14 which having their outer ends pivoted to the section 16 and supporting frame 7 are not permitted of forward movement and following the line 90 of least resistance will raise the frame 16 to the position depicted in Fig. 5. The links 18 will also have the distance between their pivots 17 increased and the upward movement of the section 16 will be limited by 95 the pivots 19 striking the inner ends of the slots 22. When the section 24 reaches the fully extended position the pivot 27 of the bar 26 will drop below the pivot 23 between the sections 16 and 24 and thus lock the links 100 13 and 14 in their extended position as any weight which is placed upon the bed springs which will naturally tend to collapse the links will merely place a strain upon the bar 26 as will be obvious.

The support 25 for the outer end of the section 24 consists of two supporting legs 28 formed of angle iron and having their upper ends pivoted to the section 24 as at 105 29 and the legs 28 are connected together by 110 means of a brace 30. The legs 28 are permitted a free movement to fold against the under side of the section 24 but are limited in their outward movement to a position just outwardly of an imaginary line drawn vertically through the pivot 29 so that weight placed upon the spring will not tend to collapse the same. When the sections 16 and 24 are folded together support 25 is folded 115 against the under side of the section 24 which is its top side when in folded position as best shown in Fig. 4.

The spring frame is braced adjacent the pivot 23 by means of a rod 31 having its ends pivoted as at 32 to one of the spring 125 sections and the brace rod is provided with an offset portion 33 intermediate its ends so that the same will be out of the way of the give of the spring 34 carried by the sections 16 and 24. Were the offset portion of 130

the brace rod 31 to be free considerable inconvenience would be experienced in folding the bed so I provide a means for guidance to prevent its interference with the functioning of the other parts of my invention, which means includes a guide link 35 having a pivotal connection with a link 36 secured to the outer end of the supporting member 6 and a pivotal connection 37 with the offset portion 33 of said rod. The operation of this will be at once apparent as when the section 16 is lowered by the means hereinbefore described the member 35 will guide the lower end of the offset portion 33 inwardly to the position depicted in Fig. 4.

From the description taken in connection with accompanying drawing it will be at once apparent that I provide a disappearing bed which may be concealed within the walls of a room, or else be concealed within the bottom of a davenport. In the latter the seat of the davenport forms no part of the bed as is the case of structures of this class now in use and therefore the davenport may be provided with the best of finish without danger of being damaged by constant use as a bed.

What I claim for my invention is:

1. A device of the class described, comprising a supporting member, a spring frame including two connected sections, pairs of pivotally connected together link members having their outer ends pivoted to the supporting member and to one of the frame sections, a second pair of pivotally connected together link members carried by each pair of first mentioned link members and having their outer ends pivotally secured thereto, and means operable by movement of the other frame section to raise and lower the first mentioned frame section with respect to the supporting member.

2. A device of the class described, comprising a supporting member, a spring frame including two connected sections, pairs of pivotally connected together link members having their outer ends pivoted to the supporting member and to one of the frame sections, a second pair of pivotally connected together link members carried by each pair of first mentioned link members and having their outer ends pivotally secured thereto adjacent their outermost pivots, a bar connecting the inner pivots of the adjacent pairs of link members to maintain said pivots at all times in substantial alinement, and means operable by a movement of the other frame section to raise and lower the first mentioned frame section substantially parallel with respect to the supporting member.

3. A bed comprising a supporting member, a spring frame including two hingedly connected together sections, pairs of link members having their inner ends pivotally connected and their outer ends pivotally connected with the supporting member and one of the spring sections whereby the said spring section is permitted a vertical movement with respect to the supporting member, a connecting bar pivotally connected to the adjacent pairs of link members where they are pivoted together, and a locking bar having one end pivoted to one pair of link members where they have their inner ends connected and its other end pivoted to the other of said spring sections.

4. A bed comprising a supporting member, a spring frame including two hingedly connected together sections, pairs of link members having their inner ends pivotally connected and their outer ends pivotally connected with the supporting member and one of the spring sections whereby the said spring section is permitted a vertical movement with respect to the supporting member, a connecting bar pivotally connected to the adjacent pairs of link members where they are pivoted together, and a locking bar having one end pivoted to one pair of link members where they have their inner ends connected and its other end pivoted to the other of said spring sections, said locking bar retaining the first mentioned spring section in raised position when the spring sections are extended and lowering the said sections when the other section is moved to folded position.

5. A bed comprising a supporting member, a spring frame including two hingedly connected together sections, pairs of link members having their inner ends pivotally connected and their outer ends pivotally connected with the supporting member and one of the spring sections whereby the said spring section is permitted a vertical movement with respect to the supporting member, a connecting bar pivotally connected to the adjacent pairs of link members where they are pivoted together, and a locking bar having one end pivoted to one pair of link members where they have their inner ends connected and its other end pivoted to the other of said spring sections outwardly of its hinge connection with the first mentioned spring section whereby the said first mentioned spring section will be locked in raised position when the sections are extended.

In testimony whereof, I affix my signature.

OTTO KCONRAD.
